ALBERT T. STEARNS, OF DORCHESTER, MASSACHUSETTS.

Letters Patent No. 78,616, dated June 2, 1868.

IMPROVEMENT IN CUTTER-HEADS FOR PLANING-MACHINES.

The Schedule referred to in these Letters Patent and making part of the same.

TO ALL WHOM IT MAY CONCERN:

Be it known that I, ALBERT T. STEARNS, of Dorchester, in the county of Norfolk, and State of Massachusetts, have invented an Improved Cutter-Head for Making Wooden Conductors and similar articles; and I do hereby declare that the following, taken in connection with the drawings which accompany and form part of this specification, is a description of my invention sufficient to enable those skilled in the art to practise it.

The invention relates particularly to the construction and arrangement of the cutters of the cutter-head or stock of machines used in the manufacture of wooden spouts or conductors, of that class in which semi-cylindrical tubes are formed, two of which placed together make a whole tube, with a tongue and a groove on each half, fitting into a corresponding tongue and groove on the opposite half, to make the joint between them, as seen in the pieces marked C, in United States Letters Patent, No. 31,449, of 1861.

In the common rotary cutter-head or stock, which has been in use upon these machines, the three cutters, on each side of the head, have been placed in the same plane of attachment, each secured to the head by a separate independent screw or bolt, and each cutter or bit, at the side of the centre cutter, being in one piece, with a notch in the cutting-edge of the tongueing-bit, for forming the tongue, and a projection on the cutting-edge of the grooving-bit, to form the groove, the three cutters being arranged side by side, with their adjacent edges in contact.

The objections to this construction and arrangement are as follows:

First, that a separate bolt is required to fasten each cutter.

Second, that as each side-cutter is made in one piece, with angles in its cutting-edge, it is difficult to sharpen the edge and keep it in good condition.

Third, that the cutters being arranged in contact, with no lateral support other than that of each cutter against its fellow, any starting or lateral twisting of one affects all the others.

Lastly, that as the cutters are arranged in the same plane, the cutting-edge of the main cutter has to be projected so far beyond the edges of the side bits, that the cutters cannot advantageously act together, the main cutter, when it acts, being at too obtuse an angle to the plane of the stock upon which it works.

The object of my invention is to obviate these defects, and I accomplish this result by making the jointing, tongueing, and grooving-cutters in separate pieces, confining the two sets on each side of each centre or main cutter by a single bolt, through which they project like bolt-keys; by supporting each cutter or set of cutters (laterally) directly against a cheek or cheeks on the head or stock, instead of against each other; and by placing the main cutter in a plane of attachment on the head beyond the plane of attachment of the side cutters, so that its cutting-edge can be arranged to act more in concert with the adjacent cutting-edges—my invention consisting in these several improvements in the construction and arrangement of the parts.

The drawing represents a cutter-head or stock embodying my improvements—

A showing an end view.

B, a front view.

C, a view, partly in plan and partly in section.

D, a central section, through one of the main cutters.

E shows a section of a conductor, such as is made in halves in machines using these cutters.

a denotes the head or stock, having upon each of two opposite sides of it a centre cutter, b, which ploughs out the centre of the conductor, and side bits, c c, which joint and tongue and groove the opposite edges of each half conductor.

Each main cutter, b, is secured to the head, between cheeks d d, as seen at B, and by a screw or bolt, e, the cutter fitting between the cheeks, which hold it from lateral displacement, while the screw e holds it down to the stock.

In each end of the stock grooves, f, are formed, in each of which grooves sits one of the tongueing or grooving and jointing-bits, c, each bit fitting into the groove, and being supported against the inner surface or wall thereof, or upon three of its surfaces, by the material of the stock itself.

Instead of confining each bit by a separate bolt, a screw-bolt, *h*, runs through the head, this bolt having mortises cut through it, which fit upon and receive the two bits at the opposite ends of the stock, these mortises being so disposed that upon passing the bolt through the stock, and the bits through the bolt, and applying a nut, *i*, to the screw-threaded end of the bolt, the two bits are brought tightly up against the inner walls of each bit-receiving slot in the stock.

To facilitate the grinding, sharpening, and repairing of the cutting-edges of the bits, each bit is made in separate parts, so that the whole of its edge may be presented to the surface of a grinding-wheel or stone. Thus each grooving and jointing-bit has a centre-bit, *k*, for cutting out the groove, and upon each side of this a straight-edged jointing-bit, *l*, while each tongueing and jointing-bit is made in two pieces, *m*, each of which has made, on the inner end of its jointing edge, an inclined cutting-edge, *n*, the two of which make a V-shaped cutter, which cuts the tongue, all of these bit-members, on each side of the cutter-head, being held in place by the one bolt, *h*, as will be readily seen.

In the old cutter-stock, (as has been before observed,) each main cutter is placed in the same plane with the bit, on each side of it, but in my stock I place each main cutter above the plane of the side cutters, as seen at B and D, I being thereby enabled to bring its cutting-edge much nearer to the stock, and in radial line with the cutting-edges of the side cutters, which arrangement enables the cutter to co-operate more advantageously with the other cutters, and also enables it to work more nearly parallel with the wood upon which it operates.

I claim the combination of the slotted screw-bolt with the cutter-head and side cutters, constructed and arranged substantially as set forth.

Also, the cutter-head, constructed with the side cutters, arranged relatively to the centre cutters, substantially in the manner and for the purpose set forth.

A. T. STEARNS.
